NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

SHUT-OUT CYLINDER.

Application filed May 20, 1927. Serial No. 192,851.

This invention relates to improvements in cylinder locks, the object being to provide a simple and effective means whereby by the use of a special key the lock may be so set that it cannot be operated by the ordinary key.

In the accompanying drawings—

Fig. 1 is a side elevation, partly broken away and in section, showing the "ordinary" key in position;

Fig. 2 is a cross section of the plug in the plane of the tumblers shown in Fig. 1;

Fig. 3 is a view similar to Fig. 1 showing the "special" key in place;

Fig. 4 is a cross section of the plug on the plane of the tumbler appearing in Fig. 3;

Fig. 5 is a side view of the cylinder partly broken away, showing the parts in position to prevent operation by the ordinary key;

Fig. 6 is a section showing the parts in position to prevent operation by the ordinary key.

1 represents the main body of the cylinder. 2 is the key plug rotatable therein. 3 is the conventional roll-back secured to the rear end of the plug 2 so that when the plug is rotated the roll-back will be actuated. 4 represents what I will call the "ordinary" key. Under normal conditions, it is desirable that the lock shall be operable by this key and when so operable said key may be pushed fully into place as indicated at Fig. 1 so that it will operate all of the tumblers. One of the tumblers and its cooperating follower means is so constructed that it will operate at certain times as a "shut out" means to prevent the full insertion of the ordinary key 4, and this particular tumbler and its follower is shown in the several views, in which 6 represents the innermost pin tumbler of a series of otherwise ordinary pin tumblers. The follower for this tumbler 6 comprises the two pieces 7 and 8. 9 is the usual follower spring. In the plug is a circumferential groove in the zone of the pin tumbler 6 and slightly wider than the tumbler hole. The depth of this groove is equal to the thickness of the follower section 8. Located in this groove is a flat ring or band which is preferably made up of two sections 10-11, the outer surface of said ring being flush with the circumferential wall of the plug when the ring is in place. When either key is in operative position in the plug, it will be noted that the back edge

of the same extends out into the grooved portion, and to give clearance therefor, I provide a recess 12 in the ring section 11 of greater length than the thickness of the key so that if it were not for the tumblers, the 60 plug could turn on the ring 2 to a limited extent. In the ring section 10 I provide a pin passage for the tumbler as seen in Fig. 2. When the key 4 is in place, it will lift the tumbler 6 so that it will move the lower section 8 up to a point just outside of the sleeve section 10. At such a time, it may be assumed that the key will otherwise lift the other plungers to the position where the plug is free. Thus, the key 4 may then be 70 turned to in turn rotate the plug and move the roll-back 3. I have thus described the normal operation of the lock with the ordinary key 4.

Now, assuming it is desired to operate the "shut out" mechanism to prevent the lock from being operated by the key 4:—To do this, I use what I will term a "special" key 14 shown in Fig. 3, wherein it will be seen that the forward end of this key 14 is cut back so that when it is pushed into place it will not lift the tumbler 6, thus leaving the follower section 8 in the hole in the sleeve section 10. Since the special key 14 will operate the other tumblers to free the plug, it follows that when the key 14 is in place, as shown in Fig. 3, the plug may be turned. Turning the plug and the sleeve clockwise as viewed in Fig. 4 will move the sleeve sections 10-11 to the position indicated in Fig. 6. Turning the key back again to the position shown in Fig. 3 will restore the plug to the position where the key may be withdrawn, but this counter-clockwise movement of the plug still leaves the sleeve 10 with the follower section 8 in the position indicated in Fig. 6 so that the tumbler 6, when the key 14 is removed, will stand inside of a solid part of the sleeve section 10. Thus, if an attempt is made to insert the key 4 into the cylinder as shown in Fig. 5, it will abut against the lower end of the tumbler 6 (or the ball bearing now commonly used at the lower end of such tumblers) and will be thereby locked from full insertion, and consequently it cannot unlock the plug so that it may be turned. Ordinarily, mere friction will serve to hold the sleeve sections 10-11 in their two operative positions. To restore the parts to a position where they may be operated by an or-

inary key, the holder of the special key 14 inserts his key in the position shown in Fig. 3 and then turns it in a counter-clockwise direction, which will return the ring and follower section 8 to a position in line with the regular follower section 7, where it will remain while the owner of the special key 14 turns the plug back to the position where said key may be withdrawn. This will leave the plug 6 and follower sections 7-8 in line, as shown in Fig. 1, so that the lock may then be operated by the "ordinary" key 4.

It will be noted that the circumferentially mounted and movable ring section 10 operates as a shield when it stands in the position indicated in Figs. 5 and 6, will then block tumbler 6 in the key plug when the slot stands in the normal position, that is to say, in a position in which the key or keys are insertible or removable.

While I have shown the invention in a preferred form, it should be understood that I intend it to cover such modifications as may be legitimately regarded as within the spirit 25 of the invention and the scope of the following claims.

What I claim is:

1. In a cylinder lock, a cylinder, a plug, a pin tumbler in the plug, a two-part follower coacting with said tumbler, a shield carried by said plug and circumferentially movable thereon, one of the parts of said follower being of a thickness not in excess of the thickness of the shield, said shield being movable on said plug by the operation of one key to overstand the pin tumbler in the plug when the key slot therein stands in a key-insertible position to thereby prevent the operation of that pin tumbler by a different key.
2. In a cylinder lock, a cylinder, a plug, a pin tumbler in the plug, a follower in the cylinder, a shield between the plug and the cylinder and operable by the movement of the plug by the use of a special key to cause said shield to overstand the pin tumbler when the key slot in the plug stands in the normal position, to prevent at such time the operation of that pin tumbler by the key designed to normally operate said lock.
3. In a cylinder lock, a cylinder, a plug, a follower in the cylinder, a pin tumbler in the plug, a shield located between the plug and said cylinder and movable by the use of a special key to a position where it will overstand the pin in the plug when the latter is in the normal position, to prevent the full insertion of a key ordinarily used to operate said lock.
4. In a cylinder lock, a cylinder, a plug, a follower in the cylinder, a pin tumbler in the plug, a shield located between the plug and said cylinder and movable by the use of a special key to a position where it will

overstand the pin in the plug when the latter is in the normal position, to prevent the full insertion of a key ordinarily used to operate said lock, said shield being mounted in a recess on the plug and circumferentially movable therein.

5. In a cylinder lock, a cylinder, a plug, a follower in the cylinder, a pin tumbler in the plug, a shield located between the plug and said cylinder and movable by the use of a special key to a position where it will overstand the pin in the plug when the latter is in the normal position, to prevent the full insertion of a key ordinarily used to operate said lock, said follower comprising two parts, one part being of a thickness not in excess of the thickness of the shield.

6. In a pin tumbler lock, a cylinder having a follower passage therein and a follower in said passage, a rotatable plug in said cylinder, said plug having a longitudinal key passage and a transverse pin passage registering with the follower passage in the cylinder at certain times, a pin in said passage for operating the follower when said pin is lifted by a key, a shield mounted on said plug for circumferential movement thereon, said shield having a passage for the follower and pin tumbler, said shield being movable to a position where a solid portion thereof overstands the pin passage when the plug is in normal position, to thereby prevent the full insertion of the key ordinarily designed to operate said pin tumbler.

7. In a pin tumbler lock, a cylinder having a follower passage therein and a follower in said passage, a rotatable plug in said cylinder, said plug having a longitudinal key passage and a transverse pin passage registering with the follower passage in the cylinder at certain times, a pin in said passage for operating the follower when said pin is lifted by a key, a shield mounted on said plug for circumferential movement thereon, said shield having a passage for the follower and pin tumbler, said shield being movable to a position where a solid portion thereof overstands the pin passage when the plug is in normal position, to thereby prevent the full insertion of the key ordinarily designed to operate said pin tumbler, said shield comprising a ring surrounding the plug, said ring being recessed to form two spaced shoulders to be engaged by a portion of a key standing in the key slot of the plug, whereby by the rotation of the plug in one direction or the other the shield will be moved on the one hand to its non-shielding position and on the other hand to its shielding position.
